SOLARIUM

Mike Tecton, 5101 45th St. NW,
Washington, D.C. 20016

Filed Sept. 16, 1965, Ser. No. 87,023

Term of patent 14 years

(Cl. D83—1)

FIG. 1 is a perspective view of a solarium embodying my new design;

FIG. 2 is a cross sectional view taken through the middle of the dome like structure resting between the two conic structures;

FIG. 3 is a front elevational view thereof;

FIG. 4 is a rear elevational view thereof;

FIG. 5 is a side elevational view thereof;

FIG. 6 is a top plan elevational view thereof.

I claim:

The ornamental design for a solarium, substantially as shown.
